US00D471281S

(12) **United States Design Patent**
Baura et al.

(10) Patent No.: **US D471,281 S**
(45) Date of Patent: ** Mar. 4, 2003

(54) **ELECTRODE FOR USE ON A LIVING SUBJECT**

(75) Inventors: **Gail D. Baura**, San Diego, CA (US); **Kevin Brian Wagner**, Chula Vista, CA (US); **Paul Ronald Jansen**, San Diego, CA (US); **Richard Eugene Trayler**, Scottsdale, AZ (US)

(73) Assignee: **CardioDynamics International Corporation**, San Diego, CA (US)

(**) Term: **14 Years**

(21) Appl. No.: **29/151,208**

(22) Filed: **Oct. 31, 2001**

(57) **CLAIM**

The ornamental design for an electrode for use on a living subject, as shown and described.

DESCRIPTION

FIG. 1 is a top perspective view of an electrode for use on a living subject showing our new design;

FIG. 2 is a top plan view of the electrode of FIG. 1;

FIG. 3 is a bottom plan view thereof;

FIG. 4 is a side view thereof;

FIG. 5 is a front view thereof;

FIG. 6 is a rear view thereof; and,

FIG. 7 is a top perspective view of the electrode of FIG. 1 mounted on a protective electrode carrier which is being shown in broken lines for illustrative purposes only and forming no part of the claimed design.
